No. 758,471.

PATENTED APR. 26, 1904.

E. A. PRAHL.

DAMPER REGULATOR.

APPLICATION FILED JAN. 28, 1903.

NO MODEL.

UNITED STATES PATENT OFFICE.

EDWARD A. PRAHL, OF PHILADELPHIA, PENNSYLVANIA.

DAMPER-REGULATOR.

SPECIFICATION forming part of Letters Patent No. 758,471, dated April 26, 1904.

Application filed January 28, 1903. Serial No. 140,909. (No model.)

To all whom it may concern:

Be it known that I, EDWARD A. PRAHL, a citizen of the United States, residing at Philadelphia, in the county of Philadelphia and 5 State of Pennsylvania, have invented new and useful Improvements in Damper-Regulators, of which the following is a specification.

This invention relates to draft regulators or dampers for steam-boiler furnaces; and the 10 object thereof is to provide an efficient mechanism for automatically controlling the draft within a boiler-furnace.

The invention consists in providing a thermostat controlled by the water within the 15 boiler and carrying adjustable means for opening the smoke-flue when the water reaches a determined temperature.

The invention further consists in the details of construction and combination of parts to 20 be referred to hereinafter, and illustrated in the accompanying drawings, forming a part of this specification, and in which—

Figure 1 represents a side elevation of a 25 draft-regulator constructed in accordance with my invention. Fig. 2 represents a vertical transverse sectional view through the mercury-cup. Fig. 3 is a vertical longitudinal sectional view through the mercury-cup and its casing.

Referring to the drawings by numerals of 30 reference, 1 designates a wall of a boiler, and removably secured thereto is a casing 2, provided with a stem or restricted portion which is threaded into the wall of the boiler, the opposite end being in the form of a cup, the upper end of which is threaded internally to receive the externally-threaded portion of a mercury-cup 3.

From the foregoing it will be understood 40 that the improved draft-regulator is to be used with any steam-boiler furnace, including a smoke-flue, and as these furnaces structurally are well understood a complete furnace has not been illustrated in the accompanying drawings.

The cup 3 is closed, with the exception of a 45 threaded opening 4, formed in the top thereof, through which projects the lower end of a vertically-arranged threaded tube 5, carrying

The tube 5 extends down to a point adjacent to the bottom of the cup 3 and serves as a means for introducing the mercury or other 55 expansible fluid from the receptacle 6 into the cup 3. Within and extending the entire length of the tube 5 is a vertically-arranged rod 7, projecting above the receptacle 6 and carrying at its upper extremity a horizontal bar 8, which constitutes the actuating means for opening the door of the smoke-flue, as will 60 be presently explained.

Arranged at suitable intervals on the tube 5 are supports or brackets 9 and 10, having vertical openings at their free ends, through which projects a vertical supporting-bar 11, 65 adjustably secured in said openings by means of set-screws 12, adapted to bind against and hold the rod in adjusted position. Near the upper extremity of the rod 11 is a pulley 13, alining with a similar pulley 14 intermediate 70 the ends of the rod 11 and preferably arranged near the center of the said rod. These pulleys are disposed on opposite sides of the actuating-bar 8, carried by the rod 7, and a chain or flexible connection 15 is terminally 75 secured to one end of the said bar 8 and passes down around the pulley 14, thence up over the pulley 13, and from the latter extends and is secured to a door 16, which normally closes an opening in the smoke-flue, and is 80 provided at its top with a counterbalancing-weight 18 to make the door sensitive to the pull exerted by the flexible connection when the rod 7 and the rod 8 are raised by the expansion of the liquid within the cup 3. A 85 partition 20 is formed in the stem or restricted portion of the casing 2, so that a circulation will be set up therein as the water flows into and out of the same.

All of the parts being assembled, the operation is described as follows: Assuming that the rod 11 has been properly adjusted, the door will remain closed until the water reaches the temperature above a determined degree, when the liquid within the cup will be expanded and forced up into the tube 5. This will cause the rod 7 to move upward, carrying with it the bar 8. As the bar 8 moves upward a pull will be exerted upon the flexible connection 15, causing the door 16 to be 90 95 100

opened and permit the draft to be established through the smoke-flue instead of under the fire-box of the furnace. When the draft is cut off from the fire-box, the fire will rapidly cool, and as soon as the temperature of the water has decreased the resultant cooling of the liquid within the cup 3 will cause it to contract, thereby allowing the rod 7 to lower to its normal position, and as the force exerted by the rod 8 will be relieved the door 16 will swing back into a closed position by its own weight.

By reference to Figs. 2 and 3 it will be observed that the rod 7 is arranged to float in the mercury and is directly engaged and positively actuated thereby. This rod is slightly less in diameter than the interior diameter of the tube 5, and this construction avoids the friction of a piston, no limit being imposed to the expansion of the mercury, and the latter is free to expand even if the damper should refuse to open, thus avoiding the rupture of any of the parts. A further most important advantage practically resulting from this differentiation in diameter between the tube 5 and rod 7 is that should the damper stick the mercury would be forced to a great height in the tube, affording additional power to open the damper with no danger of injury to the parts. The space between the mercury and the top of the cup is charged with a suitable volatile material, such as ether, to form a gas and assist in the displacement of the mercury from the cup in the tube by the heat from the boiler. The depending end of the tube which extends into the cup forms a restricted channel or passage for the mercury, so that a comparatively small displacement of the mercury within the cup will effect a relatively large vertical movement of the rod.

By adjusting the rod 11 vertically in the brackets or supports 10 the device can be regulated to actuate the door when the water reaches different degrees of temperature, and, if desired, a scale can be placed upon the rod 11 to guide the operator in making proper adjustments. By reference to Fig. 1 it will be observed that the vertical adjustment of the rod 11 will cause a certain amount of slack to be effected in the connection 15 or take up the slack in the latter, so that the operating device may be set for actuation by different degrees of temperature.

In order to facilitate the assemblage and detachment of the cup 3, an angular head 21 is formed on the top of the said cup, so that the latter can be readily applied or removed from the casing 2.

If from excessive heat the mercury passes up through the tube 5, the escape thereof will be prevented by the receptacle 6, which constitutes a safety as well as a receiving recep-

tacle for the mercury or expansive fluid disposed in the cup 3.

It will be obvious that a device constructed in accordance with the above-described invention will be effective and durable and will readily perform the service for which it is intended.

Having thus described my invention, what I claim as new is—

1. In a draft - regulator, the combination with a receptacle adapted to contain mercury, of an elongated tube forming an outlet from said receptacle, an elongated rod adapted to be movably floated in said tube and spaced sufficiently from the latter to permit the passage of mercury between it and the tube, a damper, and a connection between the damper and rod. 80

2. In a draft - regulator, the combination with a receptacle adapted to contain mercury, of an elongated tube forming an outlet from said receptacle, an elongated rod adapted to be movably floated in said tube and spaced sufficiently from the latter to permit the passage of mercury between it and the tube, an arm carried by the said rod, a vertically-adjustable rod connected to one side of the tube and carrying pulleys, a damper, and a flexible connection secured to the damper and passing over the said pulleys and attached to the rod in the tube. 85

3. In a draft - regulator, the combination with a steam-boiler furnace, including a smoke-flue and damper for the latter, of a receptacle connected to the boiler and having an expansible liquid therein supporting a volatile material, an elongated tube forming an outlet from said receptacle, an elongated rod adapted to be movably floated in said tube and spaced sufficiently from the latter to permit the passage of mercury between it and said tube, a damper, and a connection between said damper and rod. 95

4. In a draft - regulator, the combination with a steam-boiler and furnace, of a damper associated with the smoke-flue of the furnace, a casing having a restricted stem secured to the boiler, and a cup provided with a receptacle adapted to contain mercury, an elongated tube attached to and forming an outlet from said receptacle, a receptacle on the upper end of the tube, an elongated rod movably floated in said tube and spaced sufficiently from the latter to permit the passage of mercury between it and the tube, and a connection between said damper and rod. 110

In testimony whereof I affix my signature in presence of two witnesses.

EDW. A. PRAHL.
